UNITED STATES PATENT OFFICE.

LAWRENCE CRAWFORD, OF NEW YORK, N. Y., ASSIGNOR OF ONE-HALF TO JAMES CRAWFORD, OF PHILADELPHIA, PENNSYLVANIA.

PORTABLE FORGE.

1,243,816.

Specification of Letters Patent.

Patented Dec. 4, 1917.

Application filed September 21, 1916. Serial No. 121,393.

To all whom it may concern:

Be it known that I, LAWRENCE CRAWFORD, of New York, in the county of New York and State of New York, have invented certain new and useful Improvements in Portable Forges, whereof the following is a specification, reference being had to the accompanying drawings.

The invention relates to portable forges of the type usually employed in heating rivets, etc.

Heretofore in devices of this character, a forced draft has been created by the use of hand operated blowers, and the object of this present invention is to substitute means, whereby air under pressure from some independent source may be employed to the same end.

A further feature of the invention resides in an improved nozzle whereby compressed air from an independent source may be regulated and diffused in a manner which will make its employment feasible in devices of the above character.

In the accompanying drawings, Figure I, is a longitudinal sectional view through a portion of a forge conveniently illustrating the application of my invention thereto.

Fig. II, is a detail view in perspective of the adjustable cone comprised by the diffusing nozzle.

Referring to Fig. I, the ordinary fire pan of the forge is indicated at 1. Air under pressure is supplied through the perforations of a centrally disposed twyer iron 2, which forms a cap piece for the vertical passage 3, in this instance provided at the bottom with a cover 5, removable to afford access for cleaning. Passage 3, communicates with a horizontal duct 6, which is directed upwardly beyond the side of the fire pan as indicated at 7. Within this bend is suspended an elbowed air nozzle 8, by means of a cover disk 9, which closes the upturned end of passage 6. Air under pressure is supplied to the nozzle 8, through a pipe 10, subject to the control of a valve 14.

The nozzle 8, comprises a housing with opposed conical openings 11, and 12, whose axes are at right angles to each other and which communicate at their apexes through a constricted throat or passage 13. The

opening 11, is stopped by a plug 15, into which the supply pipe 10, is threaded, and the opening 12, by the conical plug piece 16, 55 illustrated in perspective in Fig. II.

This plug piece comprises a threaded shoulder 17, which engages within the end of the nozzle housing and affords a means of adjusting the conical end 16, within the 60 correspondingly shaped receiving aperture 12, so that the size of the intervening annulus 18, may be regulated to vary the flow of the air. To facilitate this adjustment, plug 16, is provided with spanner wrench 65 holes 19. The air finally escapes from the passage 18, into duct 6, through a series of discharge apertures 20, in the plug. In this way the air under pressure is admitted to duct 6, in a series of small separated 70 streams, which results in a uniform passage of the air through the whole of duct 6, and which passing through twyer iron 2, provides a steady and even draft to fire pan 1. Furthermore, any tendency to produce back 75 currents or eddies in the duct is overcome and an entirely uniform draft results.

The device as a whole is supported by tubular standards 22, and a brace 23, serves as a rest for the supply pipe 10. 80

In operation, the air under pressure supplied by pipe 10, is compelled to pass through the constricted throat 13, of the nozzle and is subsequently discharged from the conical interspace 18, through the apertures 20, of the plug 16, subject to the adjustable control of the latter and diffused into the duct 6, and thereby finally directed through the openings in the twyer iron 2, 90 into the fire pan.

By this construction, I have provided a simple efficient means whereby air under pressure supplied from an independent source may be employed as a means for creating a forced draft in portable forges. 95

In practice it has been found to be economical to make the substitution characterized above, since forges of this type are invariably used where a source of supply of compressed air is readily obtainable, for example, in the erection of structural iron work where compressed air is employed in pneumatic riveters, etc. 100

While I have shown and described my in-

vention as applied to a rivet forge, it is, of course, to be understood that the same may be adapted to other devices wherein a controllable supply of compressed air may be employed for similar purposes.

Having thus described my invention, I claim:

- 1 In a portable forge, the combination of a fire pan, a conduit communicating with said pan, means for supplying air under pressure to the conduit, including a diffusing nozzle located in said conduit and comprising a housing having opposed conical cavities communicating at their apexes through a constricted passage, a supply pipe for compressed air communicating with the enlarged end of one of the cavities; and a conical plug for the other cavity, shaped in correspondence thereto and adapted to be adjusted therein to vary the size of the conical interspace thus formed, said plug being provided with a plurality of apertures by which the air is diffused into the said conduit.
2. In a portable forge, the combination of a fire pan; a conduit communicating with said pan; a diffusing nozzle located in said conduit, including a tapered cavity; means for admitting air under pressure to the constricted end of said cavity; a plug in the enlarged end of said cavity having a plurality of apertures by which the air is diffused into said conduit; and means for adjusting said plug in said cavity, whereby the amount

of air admitted to said apertures may be varied.

3. In a portable forge, the combination of a fire pan; a conduit communicating with said pan; a diffusing nozzle located in said conduit, including a conical cavity; means for admitting air under pressure to the constricted end of said cavity; a conical plug in the enlarged end of said cavity having a plurality of apertures by which the air is diffused into said conduit; and means for adjusting said plug in said cavity, whereby the amount of air admitted to said apertures may be varied.

4. In a portable forge, the combination of a fire pan; a conduit communicating with said pan; a diffusing nozzle located in said conduit and comprising a housing having a conical cavity; means for supplying compressed air to the constricted end of said cavity; and a conical plug for the other end of said cavity shaped in correspondence thereto and adapted to be adjusted therein to vary the size of the conical interspace thus formed, said plug being provided with a plurality of apertures by which the air is diffused into the conduit.

In testimony whereof, I have hereunto signed my name at New York city, N. Y., this eleventh day of September, 1916.

LAWRENCE CRAWFORD.
